UNITED STATES PATENT OFFICE.

HENRY A. BEHN, OF UNION HILL, NEW JERSEY.

GAME APPARATUS.

SPECIFICATION forming part of Letters Patent No. 425,850, dated April 15, 1890.

Application filed May 29, 1889. Serial No. 312,512. (No model.)

To all whom it may concern:

Be it known that I, HENRY A. BEHN, of Union Hill, in the county of Hudson and State of New Jersey, have invented certain new and 5 useful Improvements in Game Apparatus; and I do hereby declare the following to be a full, clear, and exact description of the invention, such as will enable others skilled in the art to which it pertains to make and use 10 it, reference being had to the accompanying drawings, which form part of this specification.

My invention relates to an improvement in game apparatus; and it consists in the combination of an operating mechanism, a revolving shaft, an endwise-moving spring-actuated key, a series of wheels placed upon the shaft and adapted to be locked in position upon and released from the shaft, the 20 figures supported upon the wheels, and the track, as will be more fully described hereinafter.

The object of my invention is to provide a game in which figures of horses, men, boats, 25 bicyclers, and animals and objects of any kind are made to race, and in which they are caused to revolve with the shaft until the key is operated, and then they are made to revolve independently of each other.

30 Figure 1 is a vertical section of a game apparatus which embodies my invention, taken to one side of the center. Fig. 2 is an inverted view. Figs. 3 and 4 are detail views of the hubs and the key. Fig. 5 is a plan view. Fig. 6 is a plan view of the operating mechanism. Fig. 7 is a perspective view of the spring-catch.

A represents a suitable inclosing-case of any desired construction, and which has its 35 top B formed into a track of any desired size.

The portions B' of the track are supported by means of the rods C, which project down from the arches D, which extend across the top 40 of the track and are connected at their inner ends with suitable supports placed at the center of the track and inside of the representation of the judges' stand. These portions of the track are supported from above in order to give room for the movement of the different 45 parts below.

The central shaft F is provided with a pinion G at its lower end, and above this pinion

are placed the stationary supporting-collars H, and between the stationary collars are placed the hubs e of the wheels I, upon 55 which the figures J are secured. Each one of these collars is provided with a conical projection or extension L both above and below, and these projections catch inside of the hubs of the wheels, as shown, so as to hold 60 the hubs out of contact with the shaft and to cause the wheels to revolve with as little friction as possible. The wheels are given any desired weight that may be preferred, so that when given an impulse or movement 65 they will have sufficient momentum to continue to revolve for some length of time.

Cut in one side of the central shaft is a groove N, and in this groove is placed a key O, which has an endwise-sliding movement 70 and which when left free to move is forced downward by the spiral spring P, placed upon the upper end of the shaft. This key is shaped as shown in Fig. 3, and when forced upward as far as it can move the projections 75 a upon its side engage with the hubs of the wheels; but when the key is forced downward by the spring the projections do not catch in the grooves R made in the hubs of 80 the wheels, and thus leave the wheels free to 85 revolve upon the shaft. The projections upon the key O are separated just sufficiently far to allow the hubs of the wheels to fit in between them, so that when the key is raised these 90 projections enter the grooves in the wheels and cause them to revolve with the shaft; but when the key is forced downward each wheel is left free to revolve independently of each of the others. As shown in Fig. 3, the projections a upon the key O are shown in 95 solid lines catching inside of the collars H only, thus leaving the wheels e free to revolve upon the shaft F. As soon as the key is raised so that the projections a catch wholly inside of the hubs e, or partially in the hubs 100 and partially in the collars, as shown in Fig. 1, the wheels are all locked to the shaft so as to only revolve with it. The lower end of the key projects downward a suitable distance below the lower end of the shaft and strikes 105 against the end of the pivoted lever S. In order to hold the inner end of the lever S in a raised position, a spring-catch T is made to catch over its outer end and thus lock the

key. This spring-catch (shown in Fig. 7) consists of a bolt *g*, which moves back and forth on the base-plate *h*, provided with the keepers *i*, and which has its inner end bent upward, so as to catch over the top of the outer end of the lever *S*. Projecting from one side of the bolt *g* is an arm *j*, to which one end of the spring *h'* is fastened, and the other end of this spring is fastened to the plate *h*.

10 To a projection extending above the bolt is fastened the rod *l*, which has its outer end to project through the casing and by which the bolt is operated. When the bolt is left free to move, the spring *h'* forces it inward, so that as soon as the outer end of the lever *S* is depressed the bolt at once snaps over its top and holds it in that position so that the key *O* is forced upward by the inner end of the lever *S* and compresses the spring *P*, and the projections *a* catch only in the collars *H*. When the spring-latch *T* is drawn backward, the spring upon the upper end of the shaft forces the key downward, so as to release the wheels from the shaft. When it is desired to lock the wheels to the shaft, so as to cause the wheels to revolve with it, it is only necessary to depress the outer end of the lever, so that the catch *T* will catch above it, and then when the shaft is made to revolve by the operating mechanism the wheels carrying the figures revolve with the shaft. After the shaft and wheels have been given a sufficient momentum the lever *S* is freed from the catch, and then the key is forced downward and every wheel revolves independently of the other, making it a matter of the utmost uncertainty which one will stop first.

The operating mechanism for revolving the shaft and the wheels consist of a large gear-wheel *V*, which has a ratchet-wheel *W* secured to its top. The pivoted lever *Y*, carrying the dog *Z*, is placed upon the same pivot as the wheel and the ratchet. When the lever is moved in one direction, the wheel and ratchet are caused to revolve, and when the lever is moved in the opposite direction to take a fresh hold the ratchet slips idly around. When it is desired to start the figures in rapid motion around the track, one or more vigorous movements are given to the outer end of the lever *Y*, and then the catch *T* is moved outward, so as to release the end of the lever *S*, when each of the wheels is released from the key, and then they revolve independently of the shaft.

Pivoted to one side of the track is a rod *M*, against which the animals or others figures used are moved, so as to bring the grooves in the hubs of the wheels in a line with the key, and so that the key can be moved endwise and lock all of the hubs in position at the

same time. Unless all of the animals or figures are moved against this rod the grooves in the hubs are not brought into a line with the key, and hence the wheels cannot be locked 65 to the shaft or the animals given a fair start. After the animals have been moved into position and the outer end of the lever *S* is depressed, so as to raise the key, the rod *M* is moved out of the way, and then when the operating mechanism is set in motion all of the wheels and figures revolve together until the key is released by the lever *S*, and then they revolve independently.

Having thus described my invention, I 75 claim—

1. The combination of the track, the revolving shaft, the wheels mounted thereon and carrying the figures above the track, the endwise-moving spring-actuated key, which is 80 adapted to engage with the hubs of the wheels and lock them to the shaft, a mechanism for causing the shaft to revolve, and a mechanism for operating the key, substantially as described.

2. The combination of the operating mechanism, the key, the revolving shaft provided with a vertical groove to receive the key, a lever for moving the key endwise, a spring for returning the key to position, a series of fixed 90 collars placed upon the shaft, the revolving wheels having grooves in their hubs, the figures carried by the wheels, and the track, substantially as set forth.

3. The combination of the lever *S*, the revolving shaft provided with a pinion, and an operating mechanism for revolving the shaft, with a key placed in a groove in the shaft, the revolving wheels mounted upon the shaft and provided with grooves in their hubs to engage 100 with the key, the figures mounted upon the wheels, and the track, the key having a sliding movement in the groove in the shaft and having its lower end to rest upon the lever *S*, substantially as specified.

4. The combination of a revolving shaft provided with a vertical groove and a vertically-moving key placed in the groove with a series of wheels mounted upon the shaft and provided with grooved hubs in which the projections upon the key are adapted to catch and the mechanism for operating the key, thereby causing the wheels to revolve idly upon or to lock them to the shaft, so as to cause them to revolve with it, substantially 115 as specified.

In testimony whereof I affix my signature in presence of two witnesses.

HENRY A. BEHN.
